STREET SIGN BRACKET

Jack W. Reeves, 3120 NW. 36, Oklahoma City, Okla.

Filed Apr. 13, 1964, Ser. No. 79,462

Term of patent 14 years

(Cl. D54—1)

FIG. 1

FIG. 2

FIG. 3

FIG. 1 is a perspective view of a street sign bracket showing my new design.

FIG. 2 is an elevational view of the bracket looking at the side of the bracket opposite to that shown in FIG. 1.

FIG. 3 is another elevational view of the bracket taken at ninety degrees from the view of FIG. 2 and with a portion of the bracket shown in section to illustrate the structure.

I claim:

The ornamental design for a street sign bracket, as shown.
